UNITED STATES PATENT OFFICE.

WALTER M. DWYER, OF HILLSDALE, NEW JERSEY.

CHECK-PROTECTOR.

1,376,611.

Specification of Letters Patent.

Patented May 3, 1921.

Application filed October 28, 1920. Serial No. 420,163.

To all whom it may concern:

Be it known that I, WALTER M. DWYER, a citizen of the United States, residing at Hillsdale, in the county of Bergen and State 5 of New Jersey, have invented new and useful Improvements in Check-Protectors, of which the following is a description, such as will enable others skilled in the art to which it appertains to make and use the 10 same.

This invention relates to check protectors and the objects of the invention are to provide a check protector that is simple in construction and operation, as well as cheap of 15 manufacture, the same being easily carried in the pocket like a pencil or fountain pen and of the same general appearance.

Referring to the drawings:

Figure 1 is a longitudinal sectional view 20 of a check protector made in accordance with the invention.

Fig. 2 is an enlarged view of the lower portion of Fig. 1.

Fig. 3 is a sectional view on the line 3—3 25 of Fig. 2.

In the drawings 1 designates a handle or body portion of a check protector which comprises in the present instance a hollow cylindrical tube of relatively thin metal preferably made of approximately the diameter and size of an ordinary lead pencil or fountain pen so that the same can readily be carried in the pocket.

The lower end of the body portion 1 is 35 suitably cut and formed to provide suitable integral standards 2 which support the ends of a bearing pin 3 on which is rotatably mounted a knurled wheel 4.

The diameter of the knurled wheel 4 is 40 preferably a little less than the outside diameter of the body portion 1 to permit of a suitable tubular cap 5 being fitted to slip over the end of the body portion 1 to cover the knurled wheel 4 when not in use. In 45 order to retain the cap 5 in position the same is preferably provided adjacent its open end with an internal circular groove 6 pressed therein which is arranged to engage a similar external circular ridge 7 50 pressed in the body portion 1 as clearly shown in Fig. 1. In order to facilitate the circular groove 6 in the cap 5 being slipped over the circular ridge 7 the cap 5 is prefer-

ably provided with a short longitudinal slot 8 which permits the open end of the cap to 55 spring outward over the ridge 7 as the same is forced in place. The other end of the body portion 1 is also preferably provided with a circular ridge 9 pressed therein to engage the cap 5 when the same is not in 60 use.

The interior of the body portion 1 adjacent the knurled wheel 4 is arranged to contain a cylindrical inking pad 10 the lower end of which is arranged to engage the 65 knurled wheel 4. The interior of the body portion 1 is also arranged to contain a coiled spring 11 which acts to force the inking pad 10 into engagement with the knurled wheel 4. The upper end of the coiled 70 spring 11 is arranged to be held in position by means of a suitable screw threaded plug 12 which closes the top of the body portion 1. The lower end of the coiled spring 11 is 75 preferably arranged to be secured to the upper end of the inking pad so that when the plug 12 is removed the spring and inking pad can easily be removed.

The body portion is preferably provided near its upper end with a suitable spring 80 clip 13 which is adapted to engage the edge of the pocket of the wearer when the check protector is not in use.

The check protector above described can 85 be used on the face of checks to prevent alteration, the inked surface of the knurled wheel acting to make inked indentations that cannot be removed or erased.

The check protector above described is simple in construction and operation, the 90 same has few parts and is cheap of manufacture, the same being easily carried in the pocket like a pencil or fountain pen and of the same general appearance.

While the same has been described with 95 particular reference to the details of construction the same is not to be considered as limited thereto as many changes can be made and still fall within the scope of the invention set forth in the following claim.

What I claim is:—

A check protector comprising in combination a hollow cylindrical tube of relatively thin metal, a knurled wheel whose diameter is less than the diameter of said tube, means 105 for pivotally mounting said knurled wheel

on the end of said tube, a cylindrical inked pad in said tube, a coiled spring in said tube arranged to force said inked pad into engagement with said knurled wheel, and a 5 detachable cap arranged to slip over said knurled wheel and the end of said tube as and for the purposes set forth.

In testimony whereof I have signed this specification in the presence of two subscribing witnesses.

WALTER M. DWYER.
